FIG. 9

FIG. 10

FIG. 11

FIG. 12

FIG. 1 is a three-quarters perspective, taken from the front and left side (from the point of view of an occupant) of a chair incorporating the inventive design;

FIG. 2 is a three-quarters perspective, taken from the rear and right side of the chair of FIG. 1 on a slightly reduced scale;

FIG. 3 is a front elevation view of the chair of FIG. 1;

FIG. 4 is a rear elevation view of the chair of FIG. 1;

FIG. 5 is a plan view of the chair of FIG. 1;

FIG. 6 is a right side view of the chair of FIG. 1;

FIG. 7 is a three-quarters perspective view, taken from the front and right side of a modified design of the inventive chair, including arm rests;

FIG. 8 is a three-quarters perspective view, taken from the rear and right side, of the chair of FIG. 7 on a slightly reduced scale;

FIG. 9 is a front elevation view of the chair of FIG. 7;

FIG. 10 is a rear elevation view of the chair of FIG. 7; FIG. 11 is a plan view of the chair of FIG. 7; and FIG. 12 is a right side view of the chair of FIG. 7.

I claim:
The ornamental design for a stacking chair, as shown and described.
